(57) **CLAIM**

The ornamental design for a dual mode connector, as shown and described.

DESCRIPTION

FIG. 1 is a perspective view of a dual mode connector showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the dual mode connector viewed from another direction.

The broken line portion of the drawings is included to show portions of the dual mode connector that form no part of the claimed design.
